UNITED STATES PATENT OFFICE.

LEWIS E. WACKERLE, OF WAUKEGAN, ILLINOIS. ASSIGNOR TO CHICAGO HARDWARE FOUNDRY COMPANY, OF NORTH CHICAGO, ILLINOIS, A CORPORATION OF ILLINOIS.

SLICING MACHINE.

Application filed October 21, 1927. Serial No. 227,669.

This invention relates to that type of slicing machines, in which a rectangular brick of butter or the like is fed in a step by step manner to longitudinally and transversely arranged severing means, to be divided into a plurality of small pieces of a uniform size and weight. An example of such slicing mechanism forms the subject matter of the patent to Walstead, No. 1,288,771, of Dec. 10 28, 1918.

The present improvement has as its object, to provide a structural formation and combination of parts and elements in a slicing machine of the described type, wherein 15 simplicity of construction and efficiency in action are combined with ease of operation and adjustment to effect a change from one size of the severed pieces to another and different size is attained in a ready and easy 20 manner, all as will hereinafter more fully appear.

In the accompanying drawing:—

Fig. 1, is a plan view of a slicing machine embodying the present invention.

Fig. 2, is a rear end elevation, showing the severing yoke in a position different from that shown in Fig. 1.

Fig. 3, is a detail transverse section on line 3—3, Fig. 1.

Fig. 4, is a detail longitudinal section on line 4—4, Fig. 1.

Like reference numerals indicate like parts in the different views.

As usual in the present type of slicing machines, the stationary body or bed 1 of the mechanism is of a trough form, V shape in cross section, providing an effective support for a rectangular brick of butter or the like, as the same is intermittently fed 40 along the bed in the cutting operation of the mechanism.

The rear end of the body 1 is of an open formation, while the forward end of the same carries a fixed rectangular frame 2, 45 with a substantial connection of the two parts attained by attaching screws 3 passing through lateral lugs on the parts. And as usual in the present type of mechanisms, the frame 2 carries diagonally crossed wires 4 by which the material operated on is 50 divided into a plurality of longitudinal sections. The wires 4 are placed under tension, with a view to effective operation, by a tension screw bolt 5 of any usual arrangement. The forward face of the rectangular

frame 2 is of a plane form to provide a bearing face upon which the hereinafter described transverse severing wire 6 has sliding contact in its operation of cutting the longitudinal sections of the brick of butter, etc., transversely into small pieces.

At one side of the combined bed 1 and frame, journal ears 7 are provided for revolvably supporting the hereinafter described and longitudinally arranged operating shaft 8 of the mechanism.

The feeder head 9 by which the material operated on is moved in a forward direction to the severing wires 4 and 6, is of a rectangular plate form adapted to slide in 70 the V shape cavity of the body or bed 1, and is provided with a rearwardly extending plate portion 10 for the support of the hereinafter described rack bar 11, with said plate portion in turn formed with tubular 75 knuckles 12, in spaced relation, adapted to encircle the operating shaft 8 aforesaid, and provide a combined pivotal and guiding connection between the feeder head 9 and the body or bed 1 of the mechanism, and so 80 that said feeder head and its accessories can be swung into an inoperative position out of the trough of said body or bed 1, for cleaning and like functions.

The operating shaft 8 above referred to 85 extends longitudinally of the mechanism and has greater length than such mechanism so as to afford the required extent of guidance for the feeder head 9 and also provide a supporting means for the hereinafter described carrying yoke 13 of the aforesaid transverse severing wire 6. Said yoke or bow 13, is fixedly attached by a hub 13' to the forward end of the shaft 8 aforesaid, with its free end provided with a rearwardly extending bar 14, between the rear end of which and the hub portion 13' the aforesaid severing wire 6, extends, with its proper tensioning effected by a tension screw bolt 15 aforesaid, and as shown in Fig. 1. 90 100

Manual rotation of the operating shaft 8 may be effected by any usual and suitable means, preferably by a handle 16 mounted on the yoke or bow 13 adjacent to its free end.

At a point adjacent to its mid-length, the operating shaft 8 carries a fixedly attached worm hub 17 of the detail construction hereinafter described, with its spiral tooth or rib 18 adapted for operated engagement 110

with the adjacent teeth of the rack bar 11, above referred to.

- The rearward extension 10 of the feeder head 9 in addition to providing guiding and pivotal means for the feeder head as above set forth, also provides a supporting means for the rack bar 11 above referred to. In the present improvement said rack bar 11 is in the form of a detachable bar, 10 that is preferably formed with sets of teeth 19 and 19' in its opposite edges, with one set of teeth having a spacing different from that of the other set, so that with a reversal of the rack bar to bring one or the other of 15 said sets of teeth into operative relation with the operating spiral 18 of the worm hub 17 aforesaid, a change from one thickness to another in the slices to be severed is attained in simple and accurate manner. 20 The detachable connection between the feeder head extension 10 and the rack bar 11 is attained by means of a headed stud or bolt 20 on the extension 10 engaging in an open slot 21 in one end of the rack bar 11 in connection with an attaching thumb screw 22 25 passing through the opposite end of the rack bar and screwing into the extension 10, as illustrated more particularly in Figs. 3 and 4.
- 30 With the above described construction, the use of two or more replaceable rack bars 11, with different spacings in their rack teeth, may be provided, where an extended range in thickness in the slicing operation is desired.

The worm hub 17 above referred to is preferably of the type in which the spiral tooth 18 thereon, is formed to effect a feed of the material during each intermission of 40 the transverse cutting operation of the mechanism. In addition said spiral tooth 18 has less than a full turn around the hub 17, so that with said space in line with the rack bar 11, the rack bar is free to be adjusted 45 forward or backward independent of said spiral tooth.

Having thus fully described my invention what I claim and desire to secure by Letters Patent, is:—

- 50 1. The combination of a body, an operating shaft journalled longitudinally at the side of said body and carrying a slicing means at its forward end in operative relation to the forward end of said body, a 55 feeder head having movement along said body and provided with a rearward extension having pivotal and guiding engagement with said shaft, a rack bar removably attached to said rearward extension of the 60 feeder head, and a worm hub secured to said shaft and having operative engagement with said rack bar.

2. The combination of a body, an operating shaft journalled longitudinally at the 65 side of said body and carrying a slicing

means at its forward end in operative relation to the forward end of said body, a feeder head having movement along said body and provided with a rearward extension having pivotal and guiding engagement with said shaft, a reversible rack bar removably attached to said rearward extension of the feeder head and provided with rack teeth in its opposite edges, and a worm hub secured to said shaft and having operative engagement with said rack bar.

3. The combination of a body, an operating shaft journalled longitudinally at the side of said body and carrying a slicing means at its forward end in operative relation to the forward end of said body, a feeder head having movement along said body and provided with a rearward extension having pivotal and guiding engagement with said shaft, a rack bar removably attached to said rearward extension of the feeder head, and a worm hub secured to said shaft and having operative engagement with said rack bar, the attaching means for said rack bar comprising a headed stud and open slot connection at one end of the rack bar and a thumb screw at the other end of said rack bar.

4. The combination of a body, an operating shaft journalled longitudinally at the side of said body and carrying a slicing means at its forward end in operative relation to the forward end of said body, a feeder head having movement along said body and provided with a rearward extension having pivotal and guiding engagement with said shaft, a reversible rack bar removably attached to said rearward extension of the feeder head and provided with rack teeth in its opposite edges, a worm hub secured to said shaft and having operative engagement with said rack bar, the attaching means for said rack bar comprising a headed stud and open slot connection at one end of the rack bar and a thumb screw at the other end of said rack bar.

5. The combination of a body, an operating shaft journalled longitudinally at the side of said body and carrying a slicing means at its forward end in operative relation to the forward end of said body, a feeder head having movement along said body and provided with a rearward extension having pivotal and guiding engagement with said shaft, a rack bar removably attached to said rearward extension of the feeder head, and a worm hub secured to said shaft and having operative engagement with said rack bar, the worm hub having a spiral operating thread of a less extent than a full turn around said hub.

6. The combination of a body, an operating shaft journalled longitudinally at the side of said body and carrying a slicing means at its forward end in operative relation to the forward end of said body, a feeder head having movement along said body and provided with a rearward extension having pivotal and guiding engagement with said shaft, a reversible rack bar removably attached to said rearward extension of the feeder head and provided with rack teeth in its opposite edges, and a worm hub secured to said shaft and having operative engagement with said rack bar.

tion to the forward end of said body, a feeder head having movement along said body and provided with a rearward extension having pivotal and guiding engagement with said shaft, a reversible rack bar removably attached to said rearward extension of the feeder head and provided with rack teeth in its opposite edges, and a worm hub secured to said shaft and having operative engagement with said rack bar, the worm hub having a spiral operating thread of a less extent than a full turn around said hub.

7. The combination of a body, an operating shaft journalled longitudinally at the side of said body, a yoke secured to the forward end of said shaft and carrying a severing wire in operative relation to the forward end of said body, means for tensioning said wire comprising a tensioning screw mounted on said yoke longitudinally of the mechanism, a feeder head having movement along said body and provided with a rearward extension having pivotal and guiding engagement with said shaft, a reversible rack bar removably attached to said rearward extension having pivotal and guiding engagement with said shaft, a rack bar removably attached to said rearward extension

of the feeder head, and a worm hub secured to said shaft and having operative engagement with said rack bar.

8. The combination of a body, an operating shaft journalled longitudinally at the side of said body, a yoke secured to the forward end of said shaft and carrying a severing wire in operative relation to the forward end of said body, means for tensioning said wire comprising a tensioning screw mounted on said yoke longitudinally of the mechanism, a feeder head having movement along said body and provided with a rearward extension having pivotal and guiding engagement with said shaft, a reversible rack bar removably attached to said rearward extension of the feeder head and provided with rack teeth in its opposite edges, and a worm hub secured to said shaft and having operative engagement with said rack bar.

In testimony whereof I hereunto affix my signature.

LEWIS E. WACKERLE.
